UNITED STATES PATENT OFFICE.

GEORGE KRELL AND GUY M. MARTINET, OF SAPULPA, OKLAHOMA; SAID MARTINET
ASSIGNOR TO SAID KRELL.

DRILLING RIG.

Application filed February 28, 1927. Serial No. 171,409.

Our invention relates to rotary well drilling apparatus and more particularly to the turntable element of such apparatus.

In the practice of drilling oil wells with 5 rotary apparatus, the principal operative units which constitute a complete rig are a power unit, a draw works which is operated therefrom and which embodies a hoisting drum, and a turntable which is positioned 10 over the well hole and operable by a chain belt or other connection to the draw works and which has for its purpose the imparting of rotation to a grief stem, a string of drill pipe supported by the grief stem, and a 15 drill bit attached to the lower end of the drill pipe.

While drilling is actually in progress with the drill bit rotating and cutting a passage downward through the various earth formations toward the oil sand, the drill pipe to which the drill bit is attached and the grief stem which serves to support the drill pipe and the drill bit will move downwardly with the cutting progress of the drill bit 20 since the grief stem is so engaged by the turntable as to be slidable therethrough.

A grief stem is of such length as to permit drilling progress of sufficient extent so that when the lower limit of its downward 25 travel relative to the turntable is reached, it may, together with the string of drill pipe, be withdrawn sufficiently to allow another joint of drill pipe to be set in between the lower end of the stem and the upper 30 joint of the string of drill pipe.

In order to insert an additional length of drill pipe it is common practice to employ a separate clamping means to engage the upper end of a string of drill pipe to support 35 the same while an additional length of drill pipe is being attached. The foregoing method requires considerable extra manipulation and hoisting operations and the expenditure of considerable time and energy 40 since the clamping operations are in the most part manually performed.

It is primarily for the purpose of overcoming these objectionable features that this invention is intended and this we have accomplished by the provision of a clamping 45 means which is embodied in the table and

means mounted on the table whereby steam pressure may be used to actuate the clamp.

By using a steam pressure actuated clamp in this manner it becomes possible to position the control valve therefor at a more convenient location and preferably in close proximity to the control levers of the other apparatus, thus tending to clear the platform about the table of such obstructions and 55 to centralize the control of all the apparatus. 60

In accomplishing the above named and other objects of the invention hereinafter described, we have provided improved details of structure, the preferred forms of 65 which are illustrated in the accompanying drawings, wherein:

Fig. 1 is a detail perspective view of part of a rotary drilling rig comprising a turntable employing our improvements. 70

Fig. 2 is an enlarged plan view of the table.

tion, particularly illustrating the toggle block and its connecting elements, the clamp frame being severed to permit such disassembled illustration.

5 Fig. 16 is a detail perspective view of the table platform.

Fig. 17 is an enlarged vertical section of the steam valve.

Referring more in detail to the drawings: 10 1 designates a derrick of ordinary, rotary- 15 rig construction, comprising a platform 2 and a draw works, also of common construction, comprising a spooling drum 3 on a shaft 4, journaled in bearings 5 on posts 6. 20 Also journaled on the posts 6 is a drive shaft 7 connected with the drum shaft by high and low speed sprocket chains 8 and 9, run over fixed sprocket wheels 10—11 on the drive shaft and loose sprocket wheels 12—13 25 on the drum shaft, the sprocket wheels on the drum shaft having the usual clutch connection with their shaft, as indicated by the levers 14 and 15, both operable from adjacent the operator's position on the floor. 30 The driving shaft is operable from a source of power through transmission indicated by the chain belt 16. The drum is provided with the usual brake bands 17, anchored at one end by yokes 19 and connected 35 at the other end with a crank 20 under control of a lever 21, also located at the operator's position.

Located centrally on the derrick floor is a turntable platform 22, which fits within an 35 opening in the derrick floor and is supported by the usual derrick joists 23. The turntable comprises the usual circular table 24 having a depending annular gear ring 25, meshing with a pinion 26 on a shaft 27 journaled in 40 bearings 28 on the table platform 22 and provided with a sprocket wheel 29 whereby the table is operated from the drive shaft 7 through a chain belt 30, running over a sprocket wheel 31 on the draw works drive 45 shaft, under control of the clutch 32, which is operable by a lever mechanism 33 at the operator's position.

The table is provided with the usual bushing 34 for driving a drill stem 35, supported 50 by the usual hook 36 from a rope or cable 37 run over a sheave (not shown) at the top of the derrick and connected with the winding drum 3 in the usual manner.

Interposed in the drill stem is the usual 55 swivel head 38 through which the drilling fluid is supplied to the stem through a hose 39, as in ordinary drilling operation.

The parts heretofore described are common to any rotary drilling rig and have been 60 herein illustrated in order to impart a better understanding of our improvements.

As in ordinary practice, the table which we employ comprises a jaw ring 40 having a downwardly facing groove 41 containing a 65 bushing 42 for roller bearings 43 seated in a

bushing 44 in a groove 45 on the table platform 22. In accordance with our improvements, however, we provide the table with oil reservoirs 46 connected through bores 47 with the roller bearings for lubrication, the 70 reservoirs being closed by plugs 48 to protect the lubricant.

In the outer face of the jaw ring 40 of the rotary table we provide a circumferential groove 49 receiving keeper rollers 50 (Fig. 75 3) rotatable on studs 51 on standards 52 on the table platform to anchor the table against vertical and lateral displacement under the operation hereinafter described but without interfering with its free rotation. 80

In accordance with our invention the table platform 22 is provided with an inset shoulder 53 (Figs. 5 and 6) and supported on said shoulder is a divided clamp housing 54 (Fig. 11) comprising side walls 55 and end walls 85 56, the side and end walls having laterally turned shoulders 57 for support on the table platform shoulders 53 and the end walls 56 being of irregular, conical, downwardly converging formation for the purpose presently described. 90

The corners of the clamp housing are chamfered at 58 to fit within the correspondingly contoured opening in the table platform in order to hold the housing against 95 rotation and to effect and preserve alignment of the gear racks hereinafter mentioned. The clamp housings are slotted at 100 60 to provide ways for the gear racks and sockets for the slip frames, and the inner faces of the side walls 55 are provided with irregular, vertical grooves 61 forming cam tracks 62 for jaw trunnions and with longitudinal guide grooves 63 for toggle block 105 guide studs, presently mentioned.

Located within each half of the clamp housing is a jaw 64 (Fig. 13) comprising a semi-circular, vertical socket 65 provided with an inwardly directed shoulder 66 at its lower end for seating a slip frame, the upper edge of the jaw having a recess 67 with a socket 68 in its base and the shoulder or flange 66 having a registering socket 69 for receiving the anchor pins on the slip frame. At each side of the jaw is a trunnion 70 115 and a cam stud 71. Interposed between the end of the jaw and the corresponding side of the jaw housing is a toggle block 72, having pivot studs 73 extending laterally from both faces at its lower end (Figs. 4 and 15), the lower end of the block being located in the adjacent slot 60 at the end of the clamp housing and the studs 73 being movable in the horizontal grooves 63 in the side walls 120 of the clamp housing and in corresponding grooves 74 in the ends of the end walls whereby the studs 73 may anchor the toggle blocks and define travel of the toggle block under the conditions presently described. 125

In the inner face of the outer end of each 130

toggle block is a socket 75, seating the trunnion 70 at the adjacent end of the jaw 64, and extending from the outer face of the block and offset relative to the socket 75 is a trunnion 76, which is projected into and adapted for travel within the cam groove 61 in the end of the clamp housing. With this arrangement, when the cam block is rocked on the variable axis defined by the trunnion studs 73, the block is given the irregular vertical travel defined by the cam groove 61 and the jaw 64 is given the vertical and lateral movement defined by the cam groove.

In order to prevent the jaw from turning on its trunnion during the movement just described and to hold the slips carried by the jaw in vertical alignment, we provide the jaw with the cam studs 71 and the toggle blocks 72 each with a bowed edge 77 and reversely curved lip 78, forming a cam track over which the stud 71 on the jaw 64 is caused to travel during the opening and closing movements of the jaw to maintain the jaw perpendicular during such opening and closing movements.

Referring now to the means for opening and closing the clamp, 79 (Figs. 7 and 8) designates rack bars slidable in slots 80 in the ends of the clamp housing and having teeth 81 on their upper edges, engageable with rack segments 82 on hubs 83 of toggle block actuating arms 84 pivoted on pins 85 on the end members of the clamp housing. At their free ends the arms 84 are provided with slots 86 within which the pins 87 on the lower inner corners of the toggle blocks are slidably projected, cotter pins or the like 88 being mounted on the pins to retain the arms on the blocks without interfering with the automatic adjustment of the arms to the blocks.

A toggle block with its connecting elements just described is located at each corner of the housing and four individual rack bars are provided. At their outer ends the rack bars are provided with rack teeth 90, meshing with gear segments 91 on transverse shafts 92, journaled on the table platform 22.

Fixed on the shafts 92 at one side of the table are pinions 93, meshing with racks 94 slidable in guides 95 on the table platform.

The rack bars 94 are in longitudinal alignment and provided at their inner ends with rod-like members 96, which extend through stuffing boxes 97 in the ends of the pump cylinder 98, which is also mounted on the table platform, and are provided with pistons 99 for reciprocation within a common chamber within the cylinder.

Opening from each end of the cylinder is a port 100, and from the center of the cylinder is a port 101. Communicating with the end ports 100 is a steam line 102 leading to the port 103 of a valve 104. Opening from the intermediate port 101 of cylinder

98 is a line 105 leading to a port 106 of the valve 104 so that either the two end ports or the single central port may be placed in communication with a steam supply through the valve, according to manipulation of a valve lever.

The valve 104 comprises a chamber 107. A slide 108 in the valve chamber is provided with ports 109 and 110, adapted for separate communication with the ports 103 and 106 and having an exhaust channel 111 adapted for establishing communication between either of the ports 103 and 106 with an exhaust outlet port 112. The slide 108 is operable through a rod 113, extended laterally from the valve through a stuffing box 114 and guided in a bracket 115 constituting an extension of the valve body.

Pivoted on a standard 116 on the valve body is a lever 117, having pin and slot connection at 118 with the valve rod 113 and provided with a latch 119 cooperative with quadrant notches on the standards 116 to retain the valve in either set position. The steam chamber 107 of the valve 104 may connect with any source of steam supply.

Referring back to the construction of the clamp, 120 designates a slip frame, semi-cylindrical in form, to fit within the socket 65 of a jaw 64 and provided at its lower end with an anchor stud 121 and at its upper end with a lug 122, having a depending anchor stud 123 adapted to seat within the socket 68 in the recess 67 at the top of the clamp jaw. The inner face of the frame 120 is recessed to receive slips 124, here shown to be two in number although others may be provided, each of the slips having an anchor stud 125 on its lower end adapted to seat in a socket 126 in the lower flange 127 of the slip frame and a stud 128 on its upper end adapted to fit within an anchor slot 129 at the top of the frame.

Plates 130 are bolted to the top flange of the frame and are provided with recesses 131 for the upper slip anchor studs in order to hold the slips in place after the plates are applied, the sockets 126 and the slots 129 being of sufficiently larger diameter than the slip anchor studs in order to permit free pivotal movement of the slip anchor studs and flexibility in the slips to permit the slips to adjust themselves to a drill pipe. Each of the slip frames is provided at its upper end with a handle 132 whereby the frame may be let into and removed from the table.

Assuming the parts to be constructed and assembled as described, that the drilling has been in operation and that it is desired to add a joint to the drill pipe:

The operator lifts the drill pipe until the collar on the top joint of the pipe is exposed above the table platform. He then unscrews the part of the drilling apparatus commonly

termed the "Kelly" joint and more particularly the grief stem of the joint from the drill pipe and sets such "Kelly" joint to one side so that the cable and hook may be employed for connecting the new joint of pipe. It is apparent that when the "Kelly" joint is disconnected from the lower drilling pipe, some means must be provided for supporting the pipe. With the rig equipped with our invention, under the above conditions when the pipe is raised and before the "Kelly" joint is disconnected, the operator closes the clamp onto the pipe by turning steam through the pipe 102 into the ends of the cylinder 98 to force the pistons to the center of the cylinder. The clamp has, prior to this time, been open, as illustrated in Fig. 6 of the drawings. When the pistons 99 are shifted inwardly as described, the rack bars 94 rotate the shafts 92 at the ends of the table and the shafts 92 shift all four of the racks 79, which are individual to the four toggle blocks heretofore described, rocking said toggle blocks from the positions indicated in Fig. 8 of the drawings to the positions indicated in Fig. 7. This movement of the toggle block arms turns the toggle blocks on their variable pivot mountings. The trunnions 76 on the outer faces of the blocks travel in the cam grooves 61 in the ends of the clamp housing, moving the clamp jaws inwardly so that they eventually meet about the pipe, the trunnion studs 73 on the blocks shifting longitudinally in their grooves 63 in the clamp frame to permit the lateral variation in position of the clamp jaws during their vertical shifting movement.

It has been found in actual practice that a gripping angle of 7° is the most efficient for clamps of this type. Consequently, we extend the cam tracks in the groove 61 on the clamp housing at such angle so that movement resistant to the weight of the pipe is on a 7° incline but the incline is in the mounting of the clamp jaws rather than in the contour of the jaw or slip.

In order to preserve the vertical travel of the jaws and slips, the studs 71 on the clamp jaws are in constant engagement with the edges of the toggle blocks so that, irrespective of the vertical and lateral movement of the clamp jaws, the jaws remain perpendicular, thereby maintaining a through opening about the pipe, the guideway slots 61 being offset at their upper ends to provide a quick throw of the jaws toward or from the pipe at the upper limit of their closing or opening movement.

When the additional pipe joint has been applied and the drilling is to be resumed, the "Kelly" joint is connected with the new joint of pipe and the pipe released by shifting of the valve to admit steam through the pipe 105 to spread the pistons and the clamp

elements by an operation reverse to the closing operation heretofore described.

The valve communicates the pipe 102 with exhaust simultaneously with communication of the pipe 105 with the live steam in accordance with the practice with valves of this general type.

With our construction, repairs and substitutions may be easily and quickly made, as should one of the slips become worn, the slip frame may be removed from its jaw and the slip replaced in the frame without the necessity for extensive dismantling of the table, the slip frames being provided with handles 132 which normally seat in sockets 133 in the under face of the table bushing 34.

It is apparent, therefore, that we have provided a table wherein the drilling operations may be effected as usual and whereby the addition of new joints of drilling pipe may be effected more quickly and safely than with the types of apparatus heretofore in use.

While we have described the use of our invention in connection with the addition of pipe sections, it is apparent that the same method is employed in the pulling of the pipe, the clamp being always effective when lower joints are to be suspended in the well irrespective of the operation on the upper joints.

What we claim and desire to secure by Letters Patent is:

1. Apparatus of the character described including a clamp housing, toggle blocks having variable pivotal mounting on the housing, jaws having variable trunnion support on said blocks, and means for actuating the blocks to open and close the jaws.

2. Apparatus of the character described including a clamp housing, toggle blocks having variable pivot mounting on the housing, jaws having variable trunnion support on said blocks, means for actuating the blocks to open and close the jaws, and means on the jaws and blocks for retaining the jaws perpendicular during their opening and closing travel.

3. In apparatus of the character described, a clamp housing including inclined trunnion grooves, blocks having floating pivotal support in said housing and having trunnions movable in said grooves, jaws pivotally mounted on said blocks, and means for actuating the blocks to effect opening and closing movement of the jaws.

4. In apparatus of the character described, a clamp housing including inclined trunnion grooves, blocks having floating pivotal support in said housing and having trunnions movable in said grooves, jaws pivotally mounted on said blocks, means for actuating the blocks to effect opening and closing movement of the jaws, and means on the

- blocks and on the jaws for retaining the jaws perpendicular during their opening and closing travel.
5. In apparatus of the character described, a clamp housing including inclined guideways and horizontal grooves, blocks having pivot studs rotatably and slidably mounted in said grooves, trunnions on said blocks movable in said guideways, jaws pivotally mounted on said blocks, and means for actuating the blocks to effect opening and closing movement of the jaws.
6. In apparatus of the character described, a clamp housing including inclined guideways and horizontal grooves, blocks having pivot studs rotatably and slidably mounted in said grooves, trunnions on said blocks movable in said guideways, jaws pivotally mounted on said blocks, means for actuating the blocks to effect opening and closing movement of the jaws, the blocks having cam faces, and means on the jaws engaging said faces to retain the jaws perpendicular during their opening and closing travel.
- 25 7. Apparatus of the character described including clamping jaws mounted for opening and closing movement, mechanism for actuating the jaws comprising rack and pinion mechanism, a piston connected with the rack element of said mechanism, and means controlling flow of fluid to the pistons for effecting operation of the rack.
8. In apparatus of the character described, a clamp housing including guideways, trunnion blocks on the housing having means co-operating with the guideways to restrict movement of the blocks, jaws adjustably mounted on said blocks, reciprocating racks, arms connected with said blocks having pinion connection with the racks to effect opening and closing movement of the jaws upon reciprocation of the racks, and means for actuating the racks.
9. In apparatus of the character described, a clamp housing including guideways, trunnion blocks on the housing having means co-operating with the guideways to restrict movement of the blocks, jaws adjustably mounted on said blocks, reciprocating racks, arms connected with said blocks having pinion connection with the racks to effect opening and closing movement of the jaws upon reciprocation of the racks, means for actuating the racks comprising a cylinder, opposed pistons in said cylinder, racks connected with said pistons, pinion mechanism connecting the last-named racks with the first-named racks, means for delivering a fluid medium to the cylinder between the pistons to effect spread of the pistons and operation of the jaws in one direction, means for delivering fluid medium to the ends of the cylinder to effect operation of the jaws in the opposite direction, and means for selectively controlling the supply of fluid to the cylinder.
10. In a clamp of the character described, a housing comprising paired inclined guideways and paired horizontal guideways, blocks having studs pivotally and slidably mounted in the horizontal guideways and trunnions movable in the inclined guideways, jaws pivotally mounted on said blocks, slips removably mounted on said jaws, and means for actuating the blocks to effect opening and closing of the jaws.
11. In a clamp of the character described, a housing comprising paired inclined guideways and paired horizontal guideways, blocks having studs pivotally and slidably mounted in the horizontal guideways and trunnions movable in the inclined guideways, jaws pivotally mounted on said blocks, slips removably mounted on said jaws, and means for actuating the blocks to effect opening and closing of the jaws, the inclined guideways having laterally directed offsets at their upper ends to effect accelerated final opening and initial closing movements of the jaws.
12. In a clamp of the character described, a housing comprising paired inclined guideways and paired horizontal guideways, blocks having studs pivotally and slidably mounted in the horizontal guideways and trunnions movable in the inclined guideways, jaws pivotally mounted on said blocks, slips removably mounted on said jaws, means for actuating the blocks to effect opening and closing of the jaws, the blocks having cam surfaces, and studs on the jaws engageable with said cam surfaces to maintain the jaws perpendicular during their opening and closing travel.
13. In a clamp of the character described, a pair of jaws, means mounting the jaws for opening and closing movement, each of the jaws having a vertical socket with a base flange provided with a pin socket and a recess provided with a pin socket, a slip frame seatable on said flange having a pin for said flange socket, a lug on the frame seatable in said recess and having a pin for said recess socket, and slips removably mounted in said frame.
14. In a clamp of the character described, paired jaws, means mounting the jaws for opening and closing travel, a slip frame mounted in each of said jaws comprising top and bottom flanges, one having a socket and the other an open end slot, slips removably mounted in each frame, each comprising end pins for seating in said sockets and open end slots respectively, and means on the frame anchoring the slip pins to retain the slips in the frame.
15. In a clamp of the character described, a housing including side walls each pro-

vided with a guideway and a second guideway arranged at an angle thereto, toggle blocks having studs pivotally and slidably mounted in the first mentioned guideways, 5 trunnions on said blocks movable in the second mentioned guideways, jaws having trunnion connection with said blocks, arms pivotally mounted on the housing and hav-

ing pin and slot connection with the blocks, and pinion and rack mechanism for operating said arms. 10

In testimony whereof we affix our signatures.

GEORGE KRELL.
GUY M. MARTINET.
